Primary Examiner — Rosemary K Tarcza(74) *Attorney, Agent, or Firm* — Alix, Yale & Ristas, LLP(57) **CLAIM**

The ornamental design for the overhead housing for electric vehicle service equipment, as shown and described.

DESCRIPTION

FIG. 1 is a perspective view of an overhead housing for electric vehicle service equipment showing my new design; FIG. 2 is a front view thereof; FIG. 3 is a rear view thereof; FIG. 4 is a top plan view thereof; FIG. 5 is a bottom plan view thereof; FIG. 6 is a left side view thereof; and, FIG. 7 is a right side view thereof. The broken lines in the drawings illustrate unclaimed portions of the overhead housing for electric vehicle service equipment and form no part of the claimed design.
